UNITED STATES PATENT OFFICE.

CASWELL LEE LEONARD, OF CORINTH, MISSISSIPPI.

BREAD-SLICING BOARD.

1,345,376.

Specification of Letters Patent.

Patented July 6, 1920.

Application filed February 27, 1920. Serial No. 361,612.

To all whom it may concern:

Be it known that I, CASWELL LEE LEONARD, a citizen of the United States, residing at Corinth, in the county of Alcorn and State 5 of Mississippi, have invented certain new and useful Improvements in Bread-Slicing Boards, of which the following is a specification, reference being had therein to the accompanying drawing.

10 The present invention relates to a bread board, and aims to provide such a board having a guide for the breadknife whereby a loaf of bread can be conveniently cut into uniform slices of even thickness in a convenient and simple manner, such knife guide 15 being of simple and inexpensive construction, and being so constructed and arranged that it can be readily swung out of the way along one edge of the board, so that the 20 board can be used for other purposes, such as for pounding steak, kneading dough, and the like.

Another object is the provision of reinforcing or stiffening means for the ends 25 of the board, whereby to prevent the same from warping or splitting lengthwise, as well as affording means for hanging the board up when not in use.

With the foregoing and other objects in 30 view, which will be apparent as the description proceeds, the invention resides in the construction and arrangement of parts hereinafter described and claimed, it being understood that changes can be made within 35 the scope of what is claimed without departing from the spirit of the invention.

The invention is illustrated in the accompanying drawing, wherein:—

Figure 1 is a perspective view of the 40 board, showing the knife guide in active position in full lines, and in folded or inactive position in dotted lines.

Fig. 2 is a plan view of the board, portions being broken away, and portions 45 shown in section.

The board 4 is of wood or equivalent material, as usual, with the grain of the wood running lengthwise, and the ends of the board are reinforced and stiffened, to prevent 50 the lateral warping and longitudinal splitting of the board. This is accomplished by embedding stiff wires 5 in the ends of the board, and the terminals 6 of said wires are bent at an angle and pointed, and are 55 driven into the board, whereby to securely fasten such terminals in place. The wire is

secured in place between its ends by means of staples 7, or the like, driven into the wood over said wires. These wires in being thus embedded in the ends of the board and 60 secured thereto, will prevent the wood from warping laterally, as well as avoiding the splitting of the wood lengthwise, as frequently occurs with the ordinary bread board, which in being used is subject to varying 65 conditions such as moisture, heat and the like. One of the wires 5 is formed intermediate its ends with an outstanding loop 8 forming means for engaging a nail or hook to conveniently suspend the board when not 70 in use.

The board is provided at one longitudinal side edge with a knife guide 9, formed of a length of wire or similar stock. The wire is bent back and forth upon itself so as to 75 have four parallel portions constituting two upstanding loops or guide members 10 having a guide slot 11 between them, which is open at its upper end, said guide 9 projecting upwardly or perpendicularly from 80 the board when it is in a horizontal position on the table or other support. One terminal of the wire is formed with a pivot eye 12, through which a screw 13 or similar pivot member extends, being secured to the edge 85 of the board near the upper surface thereof, whereby to pivot the guide to said edge of the board, so that it can be swung downwardly toward one end of the board along said edge thereof, as seen in dotted lines in 90 Fig. 1. The other terminal of the wire has a finger 14 extending at an angle so as to snap into an aperture or socket 15 in said edge of the board, whereby to hold the guide 95 upright. Said edge of the board has another aperture or socket 16, so located, that when the guide is moved to folded or out-of-the-way position along the edge of the board, the finger 14 can be snapped into the aperture 16, for holding the guide in such 100 position. The aperture 15 is preferably farther away from the pivot 13 than the aperture 16, thereby bracing the guide 9 when in active position, by holding the terminals thereof sufficiently far apart for this 105 purpose, and when the guide is folded down, the terminals can be moved closer together, so as to lie between the opposite surfaces of the board. For this reason, the aperture 16 can be nearer to the pivot than the aperture 14.

In using the board for slicing bread, the

loaf of bread is placed on the board adjacent to the edge having the guide 9, and the breadknife can be readily inserted into the slot 11 so that the guide will maintain the knife in a vertical plane, thereby slicing the bread evenly, and by moving the loaf longitudinally and repeating the operation, the slices can be cut of desired uniform thickness. This will avoid the irregular 5 slicing of bread as now done without the aid of a guide for the knife, and when not in use, the breadknife guide can be moved out of the way along the edge of the board, so that the board can be used for other purposes as customary.

The improved features being chiefly of wire, can be manufactured inexpensively, but will nevertheless serve the intended purposes efficiently.

Having thus described the invention, what is claimed as new is:—

1. A bread board, and a knife guide bent from wire having its terminals disposed adjacent to one edge of the board and disconnected, one terminal being pivoted to said edge of the board for the swinging movement of the guide along said edge or to a position at an angle with the board, the other terminal and edge of the board having means to interengage for holding the guide in position.

2. A bread board, and a wire knife guide

having portions extending back and forth, one end of the wire guide having means pivoted to one edge of the board, and the other end having a finger extending at an angle, said edge of the board having an aperture to receive said finger for holding the guide in position.

3. A bread board, and a knife guide bent from a length of wire extending back and forth and constituting two loops with a slot between them to guide the knife, one terminal of said guide being pivoted to one edge of the board, and the other terminal of the wire guide and the board having means to interengage for holding the guide in position.

4. A bread board, and a knife guide bent from a length of wire extending back and forth and constituting a pair of loops with a slot between them, one terminal of the wire guide having an eye pivotally secured to one edge of the board, and the other terminal having a finger extending at an angle, said edge of the board having apertures, one to receive said finger for holding the guide in perpendicular position, and the other to receive said finger for holding the guide along said edge of the board out of the way.

In testimony whereof I hereunto affix my signature.

CASWELL LEE LEONARD.
